UNITED STATES PATENT OFFICE.

SVEN J. STRID, OF CHICAGO, ILLINOIS, ASSIGNOR OF THREE-FOURTHS TO RALPH G. COBURN,
OF CHICAGO, ILLINOIS.

BRAKE-HEAD.

No. 926,299.

Specification of Letters Patent. Patented June 29, 1909.

Application filed January 13, 1909. Serial No. 472,043.

To all whom it may concern:

Be it known that I, SVEN J. STRID, a subject of the King of Sweden, residing at Chicago, in the county of Cook and State of Illinois, have invented a new and useful Improvement in Brake-Heads, of which the following is a specification.

My invention relates to improvements in the construction of brake-heads of a type 10 employed in connection with brake-beams on railway cars as holders for removable brake-shoes.

Brake-beams are commonly suspended from the trucks of railway cars, which in 15 turn are spring-supported upon the car wheel journals. For this and other reasons, where a brake-head is secured in practice rigidly to the brake-beam, the angle of engagement of the shoe with the wheel varies more or less at 20 different times whereby unequal wear of the shoe is produced with resultant well known undesirable consequences.

My object is to provide a brake-head of simple, strong and durable construction and 25 so mounted that under the force of braking pressure it will readily turn upon the brake-beam and adjust itself to the tread of the wheel while resisting any tendency to turn under the jarring action of the parts in transit.

Referring to the accompanying drawings 30 which show my invention in the form I prefer to provide—Figure 1 is an elevation of my improved brake-head shown without a brake-shoe and mounted on the end of a truss brake-beam; Fig. 2, a fragmentary side 35 elevation of the brake-head removed; Fig. 3, a plan view of a friction spring employed in the preferred construction; Fig. 4, a side elevation of the spring; Fig. 5, a view in elevation of a cap forming part of the construction; Fig. 6, a sectional view of a thimble or “muffler” forming a detail of the construction, the section being taken on line 6 in Fig. 7; Fig. 7, an inner face view of the thimble; 45 Fig. 8, a broken section taken on line 8 in Fig. 1; and Fig. 9, a view similar to Fig. 8 and illustrating a modification.

The brake-beam upon the ends of which the brake-heads are mounted is of truss form 50 and of common construction, having a compression-bar 10, square in cross-section, and a round tension-rod 11. 12 is a thimble formed in one face with a square socket 13 to receive the end of the bar 10 and having 55 an inclined opening 14 through it for the pas-

sage of the rod 11. Each end portion of the bar 10 is cut away as indicated at 15 in order to clear the tension-rod. The thimble presents a circumferential bearing surface 16, an annular projecting bearing shoulder 17 at its inner end and an annular reduced bearing shoulder 18 at its outer end. The body 19, or brake-head proper, describes the well known contour illustrated with the suspension-eye 20. The head has a central opening 21 through it of a size to fit loosely over the bearing surface 16 of the thimble. The inner end portion of the said opening is enlarged to present a shoulder 22 fitting against the shoulder 17 of the thimble, and near the outer end 23 portion of the opening is an annular inwardly projecting shoulder 23 to fit the shoulder portion 18 of the thimble and present an annular, radial face 24. In the preferred construction shown, the annular face or ring 25 portion 24 of the head is serrated, as shown.

Fitting into the outer end of the opening 21 is a disk or cap 25 to bear against the surface 24, and having an inclined opening 26 through it for the end portion of the rod 11. 80 The outer end portion of the rod 11 is threaded to receive a tightening nut 27 which bears against the outer flattened surface 28 of the cap. Interposed between the cap and the serrated surface 24 is a serrated spring 29, 85 preferably of the form indicated in Figs. 3 and 4 and having meeting ends bent to project laterally from one face of the spring and present an attaching lug 30 adapted to engage a notch 31 in the cap 25. 90

In practice, the parts are assembled as shown in Figs. 1 and 8, the nut 27 being tightened to press the cap against the brake-head surface 24 through the interposed friction spring 29. The spring is held against 95 rotation by the engagement of its lug 30 with the socket in the cap and its engagement with the surface 24 prevents turning of the brake-head upon the thimble except under great strain such as the braking pressure, by which I mean the pressure employed in applying the brakes. Any jarring to which the parts may be subjected in transit will not be sufficient to cause the brake-head 100 to turn on the thimble. 105

When brakes are applied it is desirable that the shoes shall conform closely to the treads of the wheels to present the greatest area of braking surface and prevent unequal wear of the shoes. In the present construc- 110

tion, if the shoe is adjusted to properly engage the wheel at one angle, and this angle is changed, the brake-head under the force of braking pressure will turn upon the thimble to insure proper conformity of the shoe to the tread of the wheel.

In the construction shown in Fig. 9, the serrations on the annular face portion 24 of the brake-head and the friction spring 29 are dispensed with, the tightening of the cap against the face 24 by means of the nut 27 serving to produce sufficient friction to prevent turning of the head upon the thimble except under braking pressure.

15 While I prefer to construct my improvements throughout as shown and described, they may be variously modified in the matter of details of construction without departing from the spirit of my invention as defined by 20 the claims.

What I claim as new and desire to secure by Letters Patent, is—

1. The combination with a trussed brake-beam having a compression bar and a tension 25 rod, of a non-rotatable thimble on the end of the compression bar and through which the tension-rod passes, a brake-head surrounding

said thimble to rock thereon, a non-rotatable cap on the truss-rod, and means on said rod for pressing said cap frictionally against the 30 brake-head, for the purpose set forth.

2. The combination with a brake-beam, of a non-rotatable thimble thereon, a brake-head surrounding the thimble to rock thereon, a non-rotatable cap on said brake-beam, 35 a friction-spring interposed between said cap and brake-head, and means for tightening the cap upon said spring, for the purpose set forth.

3. The combination with a brake-beam, of a non-rotatable thimble thereon, a brake-head surrounding the thimble, to rock thereon, and having an annular serrated outer face portion, a non-rotatable cap on said brake-beam, an annular serrated friction-spring secured to the cap and interposed between it and said serrated face, and means for tightening the cap upon said spring, for the purpose set forth.

SVEN J. STRID.

In presence of—

J. G. ANDERSON,
R. A. RAYMOND.
